UNITED STATES PATENT OFFICE.

JOHN COTTRELL AND JOHN MARKER, OF IONIA, MICHIGAN.

VALVE LIFTER.

Application filed February 24, 1926. Serial No. 90,412.

This invention relates to improvements in valve lifters for use upon internal combustion engines contemplating the provision of a support adapted to engage the head of the 5 valve and the outer side of the cylinder block above the valve chamber and having the lower end of an offset operating lever pivoted to its upper side and adjacent the angle in the configuration thereof while a 10 substantially L-shaped plate having bifurcated end portions receiving the operating lever at an appropriate point in its length between the upper bifurcation and an offset fork within its lower end and extending in- 15 wardly toward the cylinder block for engagement with the spring cups upon the valve stems whereby a rocking movement and downward pressure exercised upon the support by the operating lever will cause the 20 valve to be held in a desired position and the spring cup moved upwardly to facilitate the removal of the valve pin whereby the valve may be removed for inspection, regrinding or replacement. 25 The lower end of the substantially L- shaped plate and upper end of the fork have registering apertured portions therein for the reception of fastening elements in the form of cotter pins therethrough where- 30 by the fork may be adjusted to an appropriate point in its length to manipulate valve springs upon valves of various lengths.

With the above and other objects in view, 35 the invention further includes the following novel features and details of construction, to be hereinafter more fully described, illustrated in the accompanying drawings and pointed out in the appended claims.

40 In the drawing:—

Figure 1 is a fragmentary elevation of a motor vehicle cylinder block illustrating the application and manner in which my invention is applied and used in conjunction 45 therewith.

Figure 2 is a top plan view of the invention per se.

Figure 3 is a perspective of the fork per se.

50 Referring to the drawing in detail, wherein like characters of reference denote corresponding parts, the reference character 10 indicates a fragmentary portion of a motor vehicle cylinder block illustrating the 55 respective positions of a puppet valve 11, valve spring 12, valve spring cup 13 and

valve pin 14; all of the above being of the usual and well known construction and forming no part of the present application for Letters Patent but being merely shown 60 and described for purposes of illustration in bringing forward the novel advantages of the above entitled invention.

The invention resides in the provision of a valve lifter constituting a support embodying a pair of disks 15 and 16 arranged in horizontal and vertically disposed positions respectively upon the head of a valve 11 and upon the outer side of the cylinder block 10 directly above the valve chamber 70 and having a reduced portion 17 arranged upon and between the periphery at appropriate points thereon from which extend upwardly extending spaced parallel apertured ears 18 between the inner sides and adjacent 75 the upper ends of which being pivotally mounted the offset end portion of a substantially L-shaped operating lever 19 as indicated at 20, correspondingly shaped companion plates 21 receiving an appropriate 80 portion of the operating lever 19 therebetween and pivotally mounting the latter upon the pivot pin 22 extending therethrough while the lower ends of the plates 21 receive the upper twisted end portion 85 23 of an offset fork 24 and which twisted portion 23 and lower ends of the plates 21 have a plurality of registering openings 90 25 provided therein for the reception of a cotter pin 26 in order that the offset fork 24 may be set at a desired height, lengthened 95 or shortened, as the case may be, for fitting and engaging the valve spring cups 13 upon the various lengths of valves 11.

In the use and operation of the present invention it is clearly apparent and manifest that the disk 15 rests upon the upper side of the cylinder block 10 and upon the head of the particular valve to be removed or replaced while the disk 16 engages the 100 outer side of the cylinder block directly above the valve chamber for creating a support and pivotal mounting for the operating lever 19 which being adapted to swing upon the respective pivots 20 and 22 between the 105 apertured ears 18 extending upwardly from the reduced portion 17 associating the adjacent sides of the disks and between the upper ends of the plates 21 respectively in order that the same may be readily rocked to and 110 fro thereon in the dotted line position as clearly illustrated in Figure 1 of the draw-

ing for moving the offset fork 24 upwardly and downwardly for raising the valve spring cup 13 upwardly upon the valve stem and compressing the valve spring 12 whereby the 5 valve pin 14 may be readily and easily removed precedent to the dotted line position of the invention as shown for releasing the valve spring cup 13 and valve 12 upon the 10 upper end of the valve stem bushing in order that the particular valve may be removed from the cylinder block 10.

The invention is susceptible of various changes in its form, proportions and minor 15 details of construction, and the right is herein reserved to make such changes as properly fall within the scope of the appended claims.

Having thus described the invention, what is claimed is:—

- 20 1. A valve lifter for use upon and in conjunction with internal combustion engines valves comprising a pair of interassociated horizontally and vertically disposed disks adapted to be seated upon the head of a 25 valve and the corresponding outer side of the cylinder block, an operating lever pivotally mounted between the disks, and lifting means associated with the operating lever and valve mechanism.
- 30 2. A lifter for use upon valves within internal combustion engines comprising a pair of horizontally and vertically disposed interassociated disks having spaced parallel upwardly extending apertured ears therebetween, a substantially L-shaped operating lever having its offset end portion pivotally mounted between the spaced parallel apertured ears, and lifting means pivotally mounted upon the lever and adapted for 35 engagement with the valve mechanism.
- 40 3. A valve lifter for use upon and in conjunction with internal combustion engines valves comprising a support constituting horizontally and vertically disposed inter- 45 associated disks adapted to rest upon the head of a valve and outer side of the engine cylinder block and having upwardly extending spaced parallel apertured ears provided therebetween, a substantially L-shaped oper-

ating lever having its offset end portion 50 pivotally mounted between the apertured ears, a pair of offset companion plates pivotally mounted upon the opposite sides of the operating lever, and means supported between the lower ends of the companion plates 55 for engagement with the valve mechanism.

4. A valve lifter for use upon internal combustion engine valves comprising horizontally and vertically disposed interassociated disks adapted to rest upon the top of a valve and outer side of a cylinder block and having upwardly extending spaced parallel apertured ears provided therebetween, a substantially L-shaped operating 60 lever having its offset end portion pivotally mounted between the apertured ears, a pair of correspondingly shaped companion plates having their upper offset ends pivotally mounted upon the opposite sides of the 65 operating lever, a substantially offset fork having its upper end mounted between the lower ends and inner sides of the companion plates, and its opposite end being adapted for engagement with the valve mechanism. 75

5. A valve lifter for use upon internal combustion engine valves comprising horizontally and vertically disposed interassociated disks adapted to rest upon the top of a valve and outer side of a cylinder block 80 and having upwardly extending spaced parallel apertured ears provided therebetween, a substantially L-shaped operating lever having its offset end portion pivotally mounted between the apertured ears, a pair of correspondingly shaped companion plates having their upper offset ends pivotally mounted upon the opposite sides of the operating lever, and an offset fork having an upper 85 twisted and apertured end portion adjustably secured between the lower free ends of the companion plates for adaptability and application upon valve stems of various lengths. 90

In testimony whereof we affix our signatures.

JOHN COTTRELL.
JOHN MARKER.
